UNITED STATES PATENT OFFICE.

SIGMUND STERNAU, OF NEW YORK, N. Y., ASSIGNOR TO S. STERNAU & COMPANY, OF NEW YORK, N. Y., A COPARTNERSHIP.

DESIGN FOR A TOOTH-BRUSH HOLDER.

41,679.

Specification for Design.

Patented Aug. 15, 1911.

Application filed July 11, 1910. Serial No. 571,505. Term of patent 7 years.

To all whom it may concern:

Be it known that I, SIGMUND STERNAU, a citizen of the United States, and a resident of the borough of Manhattan, city, county, and State of New York, have invented a new, original, and ornamental Design for a Tooth-Brush Holder, of which the following is a specification, reference being had to the accompanying drawing, forming part thereof.

The figure is a perspective view of a tooth brush holder showing my new design.

The design comprises a plate with curved extremities and lyre shaped hooks extending out therefrom, the bases of the hooks being curved and the plate adjacent to the base of each hook being convex shaped, as shown.

I claim:

The ornamental design for a tooth brush holder, as shown and described.

SIGMUND STERNAU.
